US0D1038702S

(12) **United States Design Patent** (10) **Patent No.:** **US D1,038,702 S**
(45) **Date of Patent:** **** Aug. 13, 2024**

(54) **SPORTS BOTTLE**

(71) Applicant: **Rui Wang**, Xiangtan (CN)

(72) Inventor: **Rui Wang**, Xiangtan (CN)

(**) Term: **15 Years**

(21) Appl. No.: **29/929,175**

(22) Filed: **Feb. 20, 2024**

(51) LOC (14) Cl. **07-01**

(52) U.S. Cl.

USPC **D7/533; D7/510**

(58) **Field of Classification Search**

(57) **CLAIM**

The ornamental design for a sports bottle, as shown and described.

DESCRIPTION

FIG. 1 is a front perspective view of a sports bottle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the sports bottle, which form no part of the claimed design.

1 Claim, 8 Drawing Sheets
